RAILWAY VEHICLE RUNNING GEAR

William E. Woodard, Forest Hills, N. Y.

Application December 16, 1930, Serial No. 502,730

18 Claims. (Cl. 105—80)

This invention relates to an improved box construction for the bearings of railway vehicle axles and is particularly useful in connection with locomotive driving boxes.

The primary objects of the invention are (1) to provide an improved box construction which may be used either with roller bearings or with crown journals of the present well known and customary form; (2) the provision of improved means for controlling the lateral motion of the box construction; (3) the provision of a construction by which I am enabled to provide liners between the box and the locomotive frame pedestals which have a maximum amount of bearing surface against fore and aft thrusts of the journals; (4) the provision of a rigid box structure extending from side to side of the axle in the ends of which are located the bearings and with the parts so arranged that the box, as a whole, moves in accordance with the movements of the axle; (5) the provision of a construction of the character just described in which both vertical and rocking movements of the axle are taken care of by means which cooperate with the locomotive frame construction, said means also acting to resist the lateral motion of the axle; (6) the provision of a rigid box structure of the character just described which is provided with horizontally extending trunnion means at a point intermediate the frames adapted to cooperate with the frames in resisting lateral motion of the axle while at the same time permitting both vertical and rocking movements thereof; (7) the provision of a construction as just described in which the degree or amount of lateral motion can be definitely adjusted, as well as yieldingly resisted.

The foregoing, together with such other objects as are incident to my invention, or which may appear hereinafter, are obtained by means of structure which is illustrated in preferred form in the accompanying drawings, wherein—

Fig. 1 is a horizontal section through my improved construction taken as indicated by the line 1—1 in Figure 2.

Figure 2 is an elevational view of the structure shown in Fig. 1, with the left hand portion thereof showing a vertical mid-section through my improved box construction.

Fig. 3 is a composite view with the left hand portion thereof showing a half elevation of my improvements taken just inside the left hand wheel of Fig. 2, and with the right hand portion thereof showing a vertical central section taken

approximately as indicated by the line 3—3 in Fig. 2.

Fig. 4 is a horizontal section similar to that of Fig. 1 illustrating a modification.

Fig. 5 is a section taken on the line 5—5 of Fig. 4.

Fig. 6 is another horizontal section similar to Figs. 1 and 4 illustrating a further modification, and

Fig. 7 is a section on the line 7—7 of Fig. 6. 10

Referring in the first instance to Figs. 1 to 3 inclusive which illustrate the simplest embodiment of my invention, it will be seen that I have shown a locomotive driving axle 8 with its driving wheels 9 and that I have mounted this axle 15 in roller bearings 10, although the customary crown bearing might be used instead of the roller bearing and my invention is not to be considered as being limited to the particular type of bearing illustrated. 20

The bearings 10 at each end are housed in a common rigid interconnecting framework or box structure 11 provided at its ends with the vertical bearing flanges 12 which are adapted to cooperate with the pedestal jaws 13 in absorbing 25 the fore and aft thrusts of the driving journals 14.

Secured to the inner face of each jaw 13 is a liner or bearing plate 15 of large capacity suitably held in place in any desired manner, as by bolts which may be extended through the holes 16. 30 The flanges 12 abut against the inner faces of the liners 15 and are adapted to have perfectly free movement thereover both laterally and vertically, attention being called to the fact that there are no projecting flanges at the sides of 35 the portions 12 for embracing either the liners 15 or the pedestal jaws 13, thus permitting the use of very large plain surfaces at this point for resisting the thrust of the box structure against the frame pedestal jaws. 40

The weight of the locomotive is transmitted to the ends of the box structure 11 by means of the spring saddles 17 which straddle the frame members 18 and carry the springs 19 on their upper surface. The legs of the saddles 17 fit into suitable recesses 20 in the upper surface of the housing 11. 45

On the center line of the housing 11 are formed the horizontally extending fore and aft trunnions 21, one on each side of the axle longitudinally of 50 the locomotive. Mounted to fit on the trunnions 21 are blocks 22 capable of a motion of rotation around the trunnion, the blocks being held in place by suitable cap members 23 provided with the securing bolts 24.

The blocks 22 are restrained against lateral motion transverse of the locomotive by means of the frame cross ties 25 which extend from side to side of the locomotive between the frame members 18 to which they are adapted to be secured in any desired manner, as, for instance, by means of bolts adapted to extend through the holes 26.

Between the walls of the central extensions 21 on the cross tie members which are adapted to surround or embrace the trunnions 21 and the sides of the blocks 22 are located the wear shoes 28 held in place by the bolts 29, which shoes permit the blocks to move up and down or vertically in accordance with the movements of the axle in the locomotive pedestal jaws 13.

Any desired lateral motion for the housing 11 can be provided for by a simple adjustment of the shoes 28. In other words, substantially no lateral motion may be permitted which would involve merely a sliding clearance between the blocks 22 and the shoes 28, or, if desired, a definite degree of lateral motion can be provided for the housing 11 by fitting the shoes in the blocks so that the desired clearance will exist. Adjustment of the shoes can easily be taken care of by providing shims between the extensions 21 and the backs of the shoes. Furthermore, it will be noted that any adjustment of this kind could be made without taking the housing 11, with its axle 8, out of the locomotive pedestal jaw 13.

It will be seen that the housing 11 with its axle 8 is positioned in the frames 18 by means of a construction which reacts with the locomotive frame structure in such a way as to resist lateral motion while, at the same time, permitting both vertical and rocking movements of the axle.

The modification illustrated in Figs. 4 and 5 provides for the utilization of the wedges 30 and 31 between the frame cross ties and the blocks 22, the central extension 27a in this instance being made sufficiently greater in width to accommodate the extra thickness of the wedges. The wedges may be secured by means of the bolts 32 and one wedge may be provided with any suitable form of adjusting mechanism, such as the bolts 33 extending upwardly through the binder 34 against which adjustment can be made by means of the nuts 35.

The modification illustrated in Figs. 6 and 7 provides for a yielding resistance against lateral motion. In this construction shoes 36 between the cross tie extension 27 and the block 22 are provided with a predetermined lateral clearance 37 adjacent the extension 27, such shoes 36 being held against horizontal movement by means of the flanges 38 and against vertical movement by means of the flanges 39.

Pins 40 project through the extension 27 and are adapted to be engaged by the back of the shoes 36, the outer end of each pin 40 being formed as a spring retaining cup or pocket 41. Bearing material 42 may be inserted between the backs of the cups 41 and the outer face of the extension 27.

As will be seen from Figs. 6 and 7 there are four pins 40 at each side of the trunnions 21 and these are arranged in pairs with one pair at each side of the housing 11 fore and aft of the locomotive. Each pin 40 is provided with a spring 43 and each pair of springs 43 is adapted to fit into a retaining yoke 44 adjustably held in place by means of the bolts 45 which extend between suitable ears 46 on the yoke 44 and the extension 27. Any desired tension can be placed upon the springs 43 by means of the nuts 47. Other-

wise the construction illustrated in these figures is just the same as that which is illustrated in Figs. 1 to 3 inclusive. The operation of the device of Figs. 6 and 7, of course, is as follows: When the axle 8 moves laterally, let us say to the right as viewed in Fig. 6, it will, of course, carry with it the block 22 and force the shoe 36 against the inner ends of the pins 40. These pins, therefore, will compress the springs 43 against the retaining yoke 44 which is held fixed in its adjusted position by means of the bolts 45 as described until the limit of lateral motion permitted by lateral clearance 37 is reached. This construction, therefore, provides a readily adjustable and predetermined resistance against lateral motion so that the axle 8 with its housing 11 will be returned to its normal central position just as soon as the forces creating the lateral motion are relieved.

Attention is directed to the fact that in all the forms of the invention illustrated herein the construction is such as to divorce the means for taking care of the lateral and the rocking motions of the axle from the means for absorbing longitudinal thrusts. By this separation the portions of the structure involved in each case are independent as it were, of the other, and in no way limit or hamper the other, as would be the case were the lateral and the rocking motions of the axle, for example, taken care of by suitably disposed flanges on the faces 12 adapted to take against the sides of the pedestal jaws 13.

I claim:—

1. In a railway vehicle running gear, the combination of laterally-spaced-apart frame elements having pedestal jaws, an axle carrying a pair of wheels and movable vertically and rockingly in said jaws, a pair of bearing devices, one for each end of the axle, a housing interconnecting them and movable in accordance with axle movements, means at the ends of said housing reacting against said jaws to absorb longitudinal thrust but permitting unhampered vertical, lateral and rocking movements of the axle, and means resistive to lateral motion lying between said frame elements in a horizontal plane passing through the axle and reacting between the frame elements and said housing.

2. In a railway vehicle running gear, the combination of laterally-spaced-apart frame elements having pedestal jaws, an axle carrying a pair of wheels and movable vertically and rockingly in said jaws, a pair of bearing devices, one for each end of the axle, a housing interconnecting them and movable in accordance with axle movements, means at the ends of said housing reacting against said jaws to absorb longitudinal thrust but permitting unhampered vertical, lateral and rocking movements of the axle, and means resistive to lateral motion lying in a horizontal plane passing through the axle and reacting between the frame elements and said housing, said last means including a framing between the said frame elements, in which said housing is trunnioned substantially midway of its ends.

3. In a locomotive, the combination with the usual main frames, of a framework rigidly interconnecting the bearings for an axle together with means for positioning said framework with respect to the frames characterized by the fact that means are provided intermediate the frames in a horizontal plane passing through the axle for resisting lateral motion of the framework.

while permitting both vertical and rocking movement thereof.

4. In a locomotive, the combination with the usual side frame members, of a driving axle with its wheels, bearings inside the wheels, a transverse framework rigidly connecting the bearings and means intermediate the frames in a horizontal plane passing through the axle for positioning said framework with respect to the frames, said means permitting limited vertical, lateral and rocking movement of the axle.

5. A mounting for a locomotive driving axle including in combination with the bearings, a transverse framework rigidly interconnecting the bearings, a trunnion on said framework lying between the bearings in a horizontal plane passing through the axle, and means cooperating with said trunnion and the locomotive frame structure to position said transverse framework, said means permitting limited vertical, lateral and rocking movement of the axle.

6. In a locomotive, the combination with the main frames, of an axle with its wheels, bearings inside the wheels, a housing for said bearings mounted in said frames, a trunnion on the housing between the frames lying in a horizontal plane passing through the axle, a frame cross-tie, and interengaging means between the trunnion and the cross-tie for restraining lateral movement of the housing while permitting both vertical and rocking movement thereof.

7. In a locomotive, the combination with the usual main frame, of a framework rigidly interconnecting the bearings for an axle, together with means for positioning said framework with respect to the frames, said positioning means including a frame cross-tie, a trunnion on said interconnecting framework, a bearing block mounted on said trunnion and adapted to be embraced by said cross-tie, and bearing shoes between said block and said cross-tie, said shoes permitting up and down movements of said interconnecting framework and said bearing block permitting rocking movement of said framework and being adapted to resist lateral movement thereof.

8. In a locomotive, the combination with the usual main frame members, of an axle with its wheels, bearings inside the wheels, a housing for said bearings mounted in said frame members, a trunnion on the housing between the frame members, a cross-tie between the frame members, and a block rotatably mounted on said trunnion, said block being embraced by a projecting flange on said cross-tie and being capable of relative vertical movement in said projecting flange and said trunnion being capable of rocking movement in said block.

9. A lateral motion control device for a railway vehicle axle including in combination with the frame of the vehicle, a housing rigidly interconnecting the bearings at each end of the axle, a trunnion on the housing between the bearings having its axis in a horizontal plane longitudinally of the vehicle and means reacting between the frame and the trunnion for yieldingly resisting the lateral motion of the housing.

10. A lateral motion control device for a railway vehicle axle including in combination with the frame of the vehicle, a housing rigidly interconnecting the bearings at each end of an axle, a trunnion on the housing between the bearings having its axis in a horizontal plane longitudinally of the vehicle, and means reacting between the frame and the trunnion for controlling the

lateral motion of the housing, said last means being capable of permitting a limited amount of said motion.

11. A lateral motion control device for a railway vehicle axle including in combination with the frame of the vehicle, a housing rigidly interconnecting the bearings at each end of an axle, a trunnion on the housing having its axis in a horizontal plane longitudinally of the vehicle, and means reacting between the frame and the trunnion for controlling the lateral motion of the housing, said last means being capable of permitting a limited amount of said motion together with wedge means for adjusting the degree of lateral motion.

12. In a locomotive, the combination with the usual main frame members, of a framework rigidly interconnecting the bearings for an axle, a trunnion projecting from the interconnecting framework longitudinally of the locomotive, a cross-tie between said frame members having an opening adapted to embrace said trunnion, a bearing block mounted on said trunnion, a shoe between said block and the wall of said opening capable of limited movement laterally of the locomotive, a pin extending through the wall of said opening adapted to engage said shoe, a spring yoke fixedly connected to the cross-tie and a spring reacting between said yoke and the outer end of said pin.

13. In a locomotive, the combination with the usual main frame members, of an axle with its wheels, a bearing for each end of said axle, a framework rigidly interconnecting said bearings and adapted to partake of the movements of said axle, pedestal jaws in the frame members within which said rigid framework is fitted for both vertical and lateral movement, and means for positioning said rigid framework with respect to the frame members, said means including a trunnion on the rigid framework in a horizontal plane passing through the axle, a cross-tie between the frame members and interengaging bearing means between the trunnion and the cross-tie, said interengaging bearing means being adapted to resist lateral motion of the framework and at the same time to permit both vertical and rocking movement thereof.

14. In a locomotive, the combination with the usual main frame members, of an axle with its wheels, a bearing for each end of said axle, a framework rigidly interconnecting said bearings and adapted to partake of the movements of said axle, pedestal jaws in the frame members within which said rigid framework is fitted for both vertical and lateral movement, and means for positioning said rigid framework with respect to the frame members, said means including a trunnion on the rigid framework, a cross-tie between the frame members and interengaging bearing means between the trunnion and the cross-tie, said interengaging bearing means being adapted to resist lateral motion of the framework and at the same time to permit both vertical and rocking movement thereof, together with means for yieldingly resisting the lateral movement of said rigid framework.

15. In a locomotive, the combination with the usual main frame members, of an axle with its wheels, a bearing for each end of said axle, a framework rigidly interconnecting said bearings and adapted to partake of the movements of said axle, pedestal jaws in the frame members within which said rigid framework is fitted for both vertical and lateral movement, and means for

positioning said rigid framework with respect to the frame members, said means including a trunnion on the rigid framework, a cross-tie between the frame members and interengaging bearing means between the trunnion and the cross-tie, said interengaging bearing means being adapted to resist lateral motion of the framework and at the same time to permit both vertical and rocking movement thereof, together with wedge means for adjusting the degree of lateral movement.

16. In railway vehicle axle-journalling mechanism, spaced-apart bearing mountings respectively adjacent the ends of the axle, connection means substantially fixedly positioning said mountings relative to each other, means adjacent said mountings for resisting longitudinal thrusts thereon, and means intermediate said mountings in a horizontal plane passing through the axle associated with said connection means for resisting lateral thrusts delivered to the connection means.

17. In a locomotive, the combination with the usual main frame, of a framework rigidly interconnecting the bearings for an axle, together with means for positioning said framework with respect to the frames, said positioning means in-

cluding a frame cross-tie, a trunnion on said interconnecting framework, a bearing block mounted on said trunnion and adapted to be embraced by said cross-tie, bearing shoes between said block and said cross-tie, said shoes permitting up and down movements of said interconnecting framework and said bearing block permitting rocking movement of said framework, and spring means reacting between said shoes and said cross tie for yieldingly resisting lateral movement of the framework.

18. In a locomotive, the combination with the usual main frame members, of an axle with its wheels, bearings inside the wheels, a housing for said bearings mounted in said frame members, a trunnion on the housing between the frame members, a cross-tie between the frame members, a block rotatably mounted on said trunnion, said block being embraced by a projecting flange on said cross tie and being capable of relative vertical movement in said projecting flange and said trunnion being capable of rocking movement in said block, and means reacting between said block and said cross-tie for yieldingly resisting lateral motion of the bearing housing.

25

WILLIAM E. WOODARD.
